TROLLEY DERAILER

William C. Klein, Allentown, Pa.

Application October 21, 1942, Serial No. 462,855

14 Claims. (Cl. 246—115)

This invention relates to means whereby a trolley pole may be derailed in order to stop a trolley car and it is aimed to provide such a means as may be operable in synchronization with a trolley signal block system, through switch means directly operable by the trolley pole or manually.

In addition it is aimed to provide a derailing means adapted for suitable suspension and to the ends of which trolley wires are clamped and which means includes one or more displaceable trolley arms normally aligned with the trolley wire.

The more specific objects and advantages will become apparent from a consideration of the description following taken in connection with accompanying drawings illustrating an operative embodiment by way of example.

In said drawings:

Figure 1 is a plan view illustrating one form of the derailler;

Figure 2 is a view of the derailler primarily in side elevation;

Figure 3 is a fragmentary inverted plan view of the derailler showing the trolley arms;

Figure 4 is an end elevation of the derailler;

Figure 5 is a view taken crosswise with respect to a double track showing a derailler in operative position;

Figure 6 is a detail section taken on the line 6—6 of Figure 1;

Figure 7 is a detail section taken on the line 7—7 of Figure 1;

Figure 8 is a side elevation of the derailler of a modified form;

Figure 9 is a partial plan view showing a trolley-operable circuit controller clamped to one end of the derailler;

Figure 10 is a longitudinal section taken on the line 10—10 of Figure 9 and

Figure 11 is an end view of the circuit controller of Figures 8, 9 and 10.

Referring specifically to the drawings wherein like reference characters designate like or similar parts, the derailler consists of a suitable metallic supporting plate or body generally designated 10 having integral upstanding flange 11 at opposite ends thereof. Plate or body 10 has ears 12 in which mounted bolts or studs 13 are adjustably secured by means of nuts 14 and which studs depend from a transverse attaching bar 14', fastened by bolts or the like 15 which are accommodated in openings 16 of the bar, to cross wires or cables 17 extending across one or more tracks

18 as the case may be, and mounted by poles such as 19 on opposite sides of the track or tracks.

Fastened to the body 10 is a plate or block 20 of indurated fiber or other suitable insulation. A switch arm 21, primarily of insulation is pivotally mounted at 22 on the plate 20 and at one end has a contact or conductor 23 thereon adapted for selective engagement with a pair of contacts 24 to close an electric circuit through an electro-magnet or solenoid at 25 or with a pair of contacts 26 in order to close an electric circuit through an electro-magnet or solenoid 27. It will be noted that the contacts 24 and 26 are fastened to the plate of insulation 20 and that the solenoids 25 and 27 are suitably mounted on the body 10. Said solenoids 25 and 27, respectively have slideable armatures at 28 and 29 which through the medium of a pin and slot connection at 30 and 31, respectively, are connected to a lever 32 which is pivoted midway of its ends by a pin or stud 33 to the body 10.

The armature 28 is extended and has a link 34 screw-threaded thereto at 35, which at 36 is pivoted to the switch arm or lever 21.

25 A pair of coacting clamping sections 37 and 38 are detachably secured to each flange 11 by means of bolts or other fastenings 39. Conducting trolley wires at 40 have upwardly deflected ends 41 which are seated in grooves 42 of the plates 37 30 and 38 and clamped in place between such plates. Sections 37 have conductor portions 41' fixed and aligned with the conductors 40 to serve as extensions of the latter.

Normally aligned with the trolley wires 40 and 35 extensions 41' thereof are one or more conducting trolley arms 42 which are normally aligned therewith but adapted to be moved to and from the displaced or dotted line portion shown in Figure 3 through the action of the solenoids 25 and 40 27, which arms 42, when disaligned will derail the trolley pole engaged with the trolley through the medium of the usual wheel or slideable shoe. The arms 42 at one end are rounded and correspondingly fitted in concavities at 43 with the adjacent trolley pieces or extensions 41' and adjacent such ends, screw-threaded studs 44 rise from the arms 42 and are journaled in suitable openings in the body 10, being held in place on the body by washers 45 and nuts 46.

50 In order that the arms 42 will swing on their pivots 44 through the action of the solenoids 25 and 27, the lever 32 has ears or lugs 47 extending on opposite sides thereof and through which extend lugs or studs 48 which rise from the arms 42, the lugs or studs 48 also passing through en-

larged openings 49 of a supplemental plate 50 mounted on the body 10. The pivot 33 is mounted directly by the plate 50.

The trolley wheel or shoe can travel along the wires 40, extensions 41' and arms 42 in the usual manner when they are aligned. However, in order to derail the trolley wheel or shoe to stop the trolley car, electro-magnet 27 is energized so as to attract the armature 29, resulting in shifting the lever 21 to engage contact 23 with those at 24 and shifting lever 32 so that the lugs 47 will shift the arms 42 on the pivots 44 to the disaligned dotted lined position of Figure 3. Thereafter, arms 42 may be restored to normal position for further travel of the trolley car by energizing the electro-magnet 25 to attract its armatures 28 to return the parts to the normal position wherein arms 42 are aligned.

The parts are automatically latched in the two positions through the engagement of one of the lugs 47 with a roller 51 with which the lug engages in its movement to and from the two positions and in each of which positions, the lug is on opposite sides of the longitudinal center line of a slidable rod 52 to which said roller 51 is pivoted at 53. Rod 52 is slidably mounted in spaced brackets 54 and 55 and is surrounded by an expansive spring 56 abutting the brackets 54 and a washer 57 on rod 52, so that the adjacent lugs may displace the rod in snapping from one side thereof to the other.

Body 10 is grounded as at 58. A conductor 59 grounds solenoid 25 to the body 10 and a conductor 60 leads from such solenoid to one of the contacts 24 while a conductor 61 leads from the other contact 24 to the end that when a circuit is closed through the conductor 61 solenoid 25 is energized. The solenoid 27 is grounded to the body 10 by a conductor 62 and a conductor 63 extends from that solenoid to one of the contacts 26 while a conductor 64 extends from the other conductor 26 so that when a circuit is closed therethrough and through ground the solenoid 27 will be energized. Both conductors 61 and 64 may be connected to any single pole switch 66, the other wire 67 from the switch connecting to ground or the rails the car runs on. Said electric switch is actuated by the movement of the red arm 68 or the white arm on one type signal or the position of the semaphore on other type signals.

It will be understood that in connection with the invention, I may use any desired system or means to indicate whether the derailer is "open" or "closed" as by the automatic or manual energization and deenergization of green and red lights, respectively, or equivalent contrasting signals.

The form of derailer described is adapted to be synchronized with a trolley signal block system. A signal in such a block system is shown in Figure 5 at 65.

It will be clear that the parts described may be suitably encased or covered and to this end, a conventional casing or cover is suggested in suitable sections 66' and 67', the same being removable and fastened in place in any desired manner. The invention is also applicable where a single track is used for a trolley and the latter travels in both directions as well as for a double track with the trolley or trolleys traveling in a single direction.

The modified form of Figures 8 to 11 may be employed and the same construction of derailer is used as in the preceding figures but with a dif-

ferent form of cover or casing. In this form of the invention, the same reference characters as in the previous forms have been used, as far as they apply. In this form of the invention, the 5 plates 38 preferably have a pair of bearings 68 integral or rigid therewith in which a shaft 69 is rotatable and to which a rotor body 70 of insulation, is riveted or otherwise fastened as at 71. The rotor body in the insulation thereof has 10 a longitudinal groove or notch 71' normally engaged by projections 72 on spring fingers or contacts 73, 74 and 75. The metallic contacts 73, 74 and 75 are fastened to insulated plate or bracket 76 bolted as at 77 to the bearing 68. A 15 contact or conductor of metal 78 is screwed at 79 to the periphery of the rotor 70 and the rotor 70 is adapted to be rocked in engagement with the wheel or slide on a trolley pole, in order to engage the contact 78 with the conductors 73, 74 and 75 whereby the parts described serve as a circuit maker and breaker. To this end, an actuating arm 80 is pivoted at 90 to the rotor and it has a lug 91 engageable with a lug 92 on the rotor. Actuator arm hangs vertically by 25 gravity as shown in full lines in Figure 10 and when the wheel 80 or shoe on a trolley pole strikes it from the left, it will simply move to the dotted line position *a* and not operate the rotor while if such wheel 80 or shoe should strike actuator 80 from the right, the abutment of lug 91 with lug 92 would cause movement of the actuator to the dotted line position *b* and corresponding movement or rotation of the rotor to a position engaging contact 78 with the contacts 73, 74 and 75.

According to the arrangement of the tracks and trolleys, a circuit closure according to Figures 9, 10 and 11 may be employed at one end only of the trolley derailer or one of them may be employed at each end of the trolley derailer, in which event, the actuator 80 would operate the reverse to that disclosed in Figure 10, that is would be effective when engaged by a trolley wheel or shoe traveling from left to right and would be ineffective when the trolley wheel travels 45 from right to left.

Only one of the circuit breakers is required for double track single direction operation of a trolley and in such event the actuator 80 can be rigid with the rotor.

50 In the second form of the invention, a longer preferably one piece conventional type of cover or casing 96 may be employed in lieu of that at 66-67.

Various changes may be resorted to provided 55 they fall within the scope of the invention.

I claim as my invention:

1. Mechanism of the class described comprising a signal, and means to derail a trolley element automatically through actuation of the signal.
- 60 2. In combination with a trolley signal of a block system, means operable by the signal synchronized therewith to automatically derail a trolley element with respect to a trolley means, through actuation of the signal.
- 65 3. A trolley derailer of the class described having a body, means thereon for alignment with a trolley to constitute a portion of the latter, and means operable to displace the first mentioned means to cause derailment of a trolley element.
- 70 4. A derailer of the class described comprising a body, means to secure opposite ends of a trolley thereto, means on the body for alignment with the trolleys to form a section thereof, and means to displace the last mentioned means to cause der-75 railment of a trolley element.

5. A derailer of the class described comprising a body, clamping means at opposite ends thereof to secure trolley wires thereto, means on the body for alinement with the trolley wires, and means operable to displace the last mentioned means to cause derailment of a trolley member.

6. A derailer of the class described comprising a body, clamping means at opposite ends thereof to secure trolley wires thereto, means on the body for alinement with the trolley wires, and means operable to displace the last mentioned means to cause derailment of a trolley member, the first mentioned means having trolley portions, disposed between the second mentioned means and trolley wires.

7. A derailer of the class described having a body, means to clamp trolley wires to opposite ends of the body, trolley arm means pivoted on the body, and lever mechanism on the body connected to the arm means operable to displace the latter to cause derailment of a trolley member.

8. A derailer of the class described comprising a body adapted for connection thereto of the opposite ends of trolley wires, trolley arms pivoted to the body for normal alinement with the trolley wires, electro-magnets on the body, and mechanism operable by the magnets and connected to the trolley arms to move them to and from alined positions.

9. A derailer of the class described comprising a body adapted for connection thereto of the opposite ends of trolley wires, trolley arms pivoted to the body for normal alinement with the trolley wires, electromagnets on the body, and mechanism operable by the magnets and connected to the trolley arms to move them to and from alined positions, and electric switch means controlled by said mechanism.

10. A derailer of the class described comprising a body adapted for connection thereto of the opposite ends of trolley wires, trolley arms pivoted to the body for normal alinement with the trolley wires, electro-magnets on the body, and mechanism operable by the magnets and connected to the trolley arms to move them to and from alined positions, ears, a lever of said mechanisms equipped with said ears on opposite sides thereof, said ears being inter-connected with said trolley arms.

11. A derailer of the class described comprising a body adapted for connection thereto of the opposite ends of trolley wires, trolley arms pivoted to the body for normal alinement with the trolley wires, electro-magnets on the body, and mechanism operable by the magnets and connected to the trolley arms to move them to and from alined positions, ears, a lever of said mech-

anism equipped with said ears on opposite sides thereof, said ears being inter-connected with said trolley arms, and latch means engageable by one of the ears and on the opposite sides of which the latter is movable.

12. A derailer of the class described comprising a body adapted for connection thereto of the opposite ends of trolley wires, trolley arms pivoted to the body for normal alinement with the trolley wires, electro-magnets of the body, and mechanism operable by the magnets and connected to the trolley arms to move them to and from alined positions, a circuit make and break device mounted on the body, contacts associated with said device to control the circuits through said electro-magnets, and means to operate said device by contact with a trolley member.

13. A derailer of the class described comprising a body adapted for connection thereto of the opposite ends of trolley wires, trolley arms pivoted to the body for normal alinement with the trolley wires, electro-magnets of the body, and mechanism operable by the magnets and connected to the trolley arms to move them to and from alined positions, a circuit make and break device mounted on the body, contacts associated with said device to control the circuits through said electro-magnets, and means to operate said device by contact with a trolley member, said means comprising an actuator pivoted in place for free movement in one direction, and lug means between the actuator and circuit breaker to cause unitary movement in the opposite direction.

14. A derailer of the class described comprising a body adapted for connection thereto of the opposite ends of trolley wires, trolley wires pivoted to the body for normal alinement with the trolley wires, electro-magnets of the body, and mechanism operable by the magnets and connected to the trolley arms to move them to and from alined positions, a circuit make and break device mounted on the body, contacts associated with said device to control the circuits through said electro-magnets, and means to operate said device by contact with a trolley member, said means comprising an actuator pivoted in place for free movement in one direction, and lug means between the actuator and circuit breaker to cause unitary movement in the opposite direction, said circuit maker being a rotor, the rotor having a contact thereon and a part of insulation provided with a groove, the first mentioned contact having portions normally engaged in said groove.

WILLIAM C. KLEIN.
